UNITED STATES PATENT OFFICE.

PHINEAS B. MYERS, OF BROOKLYN, NEW YORK.

DESIGN FOR A PAPER BOX.

SPECIFICATION forming part of Design No. 26,297, dated November 17, 1896.

Application filed March 19, 1896. Serial No. 583,979. Term of patent 7 years.

To all whom it may concern:

Be it known that I, PHINEAS B. MYERS, a citizen of the United States, residing at Brooklyn, in the county of Kings and State of New York, have invented and produced a new and original Design for Paper Boxes, of which the following is a specification, reference being had to the accompanying drawing, which represents a perspective view of my newly-designed paper box.

The leading feature of my design consists of a box having the shape of a parallelepiped, with forwardly and rearwardly projecting sides and top.

d are the sides of a box made in the form 15 of a parallelepiped and having a bottom, a top *c*, and ends or heads *a b*. The sides *d* are extended beyond the heads *a b* to form the curved sections *d'* and scrolls *d''*. The top *c* is also extended beyond the heads to form 20 the flaps *c' c''*.

What I claim is—

The design for a paper box, substantially as herein shown and described.

PHINEAS B. MYERS.
